UNITED STATES PATENT OFFICE.

FRANK E. HOUSH, OF BRATTLEBOROUGH, VERMONT.

DESIGN FOR A CAMPAIGN-CARD.

SPECIFICATION forming part of Design No. 18,550, dated August 21, 1888.

Application filed July 18, 1888. Serial No. 280,336. Term of patent 7 years.

To all whom it may concern:

Be it known that I, FRANK E. HOUSH, of Brattleborough, in the county of Windham and State of Vermont, have invented and produced a new and original Design for a Campaign-Card, of which the following is a specification.

Reference is to be had to the accompanying drawing, forming a part of this specification, which represents a plan view of my design.

The leading feature of my design consists of an irregular figure representing the national flag of the United States of America waving from a staff, and three circular figures having marginal lines disposed upon the surface of the said flag-like figure, and a fourth circular figure

having marginal lines represented as resting upon the staff of the flag-like figure. The circular figures represent medallions, and are intended to contain portraits.

20

I claim—

The design for a campaign-card herein shown and described, consisting of an irregular figure representing the national flag waving from a staff, three circular figures upon the surface 25 of the flag-like figure, and a circular figure upon the staff of the flag-like figure.

FRANK E. HOUSH.
